HOBBING MACHINE

George L. Merrill, East Cleveland, Theodore F. Carlin, Cleveland, and Edward J. Batorski, Garfield Heights, Ohio, assignors to The Cleveland Hobbing Machine Co., Euclid, Ohio, a corporation of Ohio

Application December 13, 1943, Serial No. 514,004

8 Claims. (Cl. 90—4)

The present invention relates to hobbing machines and more particularly to hobbing machines of the general type shown in U. S. Patents Nos. 2,231,866 and 2,307,428.

The principal object of the invention is the provision of a novel and improved hobbing machine especially adapted for cutting splines on shafts, gun barrels, and the like, wherein an electric motor or other suitable power source is employed for rotating the tool and work spindles and for producing a relative feed movement therebetween, and comprising electrically controlled means for automatically rendering the feed means inoperative at a predetermined point in the relative movement between the tool and work spindles without stopping the rotation of the spindles.

The invention resides in certain constructions and combinations and arrangements of parts and further objects and advantages thereof will be apparent to those skilled in the art to which it relates from the following description of the preferred embodiment described with reference to the accompanying drawings forming a part of this specification in which similar reference characters designate corresponding parts, and in which

Fig. 1 is a perspective view of a hobbing machine embodying the present invention;

Fig. 2 is a vertical section through the hobbing machine shown in Fig. 1, approximately on the center line with portions shown in elevation;

Fig. 3 is a section approximately on the line 3—3 of Fig. 2 with portions shown in elevation;

Fig. 4 is a section approximately on the line 4—4 of Fig. 3 with portions shown in elevation;

Fig. 5 is a section approximately on the line 5—5 of Fig. 2;

Fig. 6 is a view approximately on the line 6—6 of Fig. 2; and

Fig. 7 is a wiring diagram of the electrical circuits of the machine.

While the invention is susceptible of various modifications and alternative constructions, it is herein shown as embodied in a machine similar to the machine shown in U. S. Patent No. 2,307,428. The preferred embodiment shown is hereinafter described in considerable detail but it is to be understood that the invention is not limited to the specific form of machine shown and it is my intention to cover hereby all modifications and alternative constructions thereof that come within the spirit and scope of the invention as defined in the appended claims.

Generally speaking, the machine shown com-

prises a frame consisting of a base A having a vertical column B detachably fixed thereto, a work head C slidably supported on vertically spaced pairs of vertical ways 10 and 11 on the column B and a tool or hob head D adjustably supported on a pair of horizontal ways 12 also on the column B and located intermediate the spaced vertical ways 10 and 11. As shown, the work W is supported between a suitable chuck 13 fixed to the upper end of a work spindle 14 and a center 15 carried by a tailstock 16 slidably supported on vertical ways 17 and 18 on the work head C and the hob H is carried by a tool spindle 20 rotatably supported in the tool or hob head D. The work and tool spindles 14 and 20, respectively, are geared together and driven from a reversible electric motor 21, hereinafter referred to as the cut motor. A relative feed movement between the work and hob spindles is effected by moving the work head C vertically by means of a lead screw 22 geared to the work spindle drive in a manner hereinafter specifically described. The machine also includes means, such as the high speed reversible electric motor 23 operatively connected to a nut 24 with which the lead screw 22 cooperates for rapidly elevating or lowering the work head C to bring the work W up to or down to the hob H and/or to return the work head to its starting position after the cutting operation has been completed and the finished piece removed.

Insofar as the mechanical features of the machine shown are concerned, they are similar to those shown in the aforesaid Patent No. 2,307,428 and will not be herein described in detail. Suffice it to say that the work and tool spindles 14 and 20, respectively, are geared together and operatively connected to the cut motor 21. The cut motor 21 is operatively connected by a flexible drive connection, designated generally as 25, to a horizontal shaft 26, the forward splined end of which shaft projects into the hob head D. The shaft 26 is rotatably supported in the frame B by an anti-friction bearing 27 and the hub 28 of a gear 30, which gear is in turn rotatably supported by an anti-friction bearing 31 in a member 32 fixed to the frame B. The forward end of the shaft 26 is rotatably supported in the hob head D by a gear 33 splined to the shaft 26 and rotatably supported in the hob head by an anti-friction bearing 34. The gear 33 is continuously in mesh with a gear 35 fixed to one end of a short shaft 36 rotatably supported in the adjustable member 37 of the hob head D, the opposite end of which shaft is provided with a gear 38 continu-

ously in mesh with a gear 40 keyed to the tool spindle 20. The tool spindle 20 is provided with a flywheel 41.

The gear 30 is also splined to the shaft 26 and is continuously in mesh with a gear 42 fixed to the upper end of a vertical shaft 43 the lower splined end of which is provided with a gear 44 rotatably supported in the work head C. The gear 44 is continuously in mesh with a gear 45 fixed to the rear end of a horizontal shaft 46 which projects forwardly through a partition 47 in the work head C and into a gear box or compartment designated generally by the reference character 48. The splined portion of the shaft 43 permits the work head C to be moved vertically. The shaft 46 is operatively connected to a horizontal shaft 50 through the medium of the work spindle drive change gears E, the driving and driven gears 51 and 52 of which are keyed to the ends of the shafts 46 and 50 respectively. The shaft 50 is rotatably supported in an adjustable cradle and is provided with a worm 54 continuously in mesh with a worm wheel 55 keyed to the work spindle 14.

The work head C is moved in timed relation to the rotation of the tool and work spindles during the cutting operation by the lead screw 22 previously referred to, operatively connected to the work spindle drive by a worm wheel 60 keyed to the upper end thereof, which worm wheel is continuously in mesh with a worm 61 fixed to a horizontal shaft 62 rotatably supported in the work head D. The shaft 62 projects through the partition 47 into the gear box 48 where it is operatively connected to the shaft 50 by the feed change gears F, the driving and driven gears 64 and 65, respectively, of which are fixed to the shafts 50 and 62, respectively.

It will be apparent from the foregoing that the direction of feed with respect to the direction of rotation of the tool and work spindles can be reversed by either inserting or removing an idler gear in the feed change gears F and that the direction of feed and the direction of rotation of the work spindle 14 can be reversed with reference to the direction of rotation of the tool or hob spindle 20 by inserting or removing an idler gear from the work spindle drive change gears E. For the purposes of permitting the use of various change gears, idlers, etc., in the work spindle drive change gears E and the feed change gears F suitable spiders or gear supporting members 66 and 67 are provided. The particular arrangement shown in the present instance forms no part of this invention and is similar to that disclosed in the aforesaid Patent No. 2,307,428.

The traverse motor 23 is operatively connected to the nut 24 with which the lead screw 22 cooperates by a worm and worm wheel combination comprising a worm 70 fixed to a shaft 71 operatively connected by a coupling member 72 to the armature shaft 73 of the motor 23. The worm 70 is continuously in mesh with a worm wheel 74 cut in the periphery of the nut 24. The weight of the work head C is carried by a thrust bearing 75 interposed between the lower side of the nut 24 and the bottom of an aperture in a bracket 76 which supports the same. The bracket 76 is detachably connected to the base A of the machine.

According to the provisions of the present invention, the worm 70 and worm wheel 74 combination is not of the self-locking type and supplemental means is provided for holding the nut 24 stationary during rotation of the lead screw

22 to produce the feed movement between the work and tool spindles 14 and 20, respectively. As shown, this means is an electric solenoid-operated brake, designated generally by the reference character G, connected to the left-hand projecting end of the armature shaft 73 of the motor 23 as viewed in Fig. 2. The solenoid-operated brake G comprises two movable brake shoes 80 and 81 adapted to engage a brake drum 82 fixed to the armature shaft 73 of the motor 23. The brake shoes are normally held in engagement with the brake drum 82 by a compression spring 83 interposed between the right-hand shoe 80 and a member 86 secured to the end of a rod 85 pivotally connected to the shoe 81. The brake shoes are actuated to disengage the brake drum 82 and thus release the brake on the armature shaft 73 by an electric solenoid 84 connected with the electric control of the machine in a manner hereinafter described. When the solenoid brake G is released, the nut 24 and in turn the armature shaft 73, etc., are free to rotate and rotation of the lead screw 22 will not effect any relative rotation therebetween and the nut 24.

From the foregoing description, it will be apparent that the relative feed movement between the work and tool spindles can be interrupted without stopping the relative rotation between the spindles by energizing the solenoid 86 to release the brake, which according to the provisions of the present invention, is accomplished automatically at a predetermined point in the relative movement between the spindles. The control for the solenoid 86 of the brake is so arranged that the brake is released whenever the motor 23 is connected to the power source, as will be hereinafter described.

The machine is started by pushing a start push button switch 90 located on a switch panel 91 mounted on the side of the machine, whereupon the traverse motor 23 operates to rotate the nut 24 at a high rate of speed and in such a direction that the work W is rapidly moved toward the hob H. Just prior to the time the work W engages the hob H a switch 92 located on the left-hand side of the column B is actuated by an adjustable stop 93 carried by the work head C, stopping the rapid traverse motor 23, and starting the cut motor 21. The up and down limits of movement of the work head C are controlled by an electric switch 94 actuated by adjustable stops 95 and 96 also carried by the work head C. The stop 95 controls the downward limit of movement of the work head C and the stop 96 the upward limit of movement. Actuation of the switch 94 during the first movement by either of the stops 95 or 96, energizes the solenoid 84 of the brake G but a timing release maintains the motor 21 energized for a predetermined period of time the duration of which period is sufficient for the work spindle to make at least one complete revolution. As previously stated, the machine of the present invention is exceptionally adapted for cutting splines on a shaft and the purpose of having the work spindle make a complete revolution after the feed of the work cut has stopped is to have all of the splines end at the same longitudinal point along the shaft. After the shaft has been cut and removed, the work head C is returned to its starting position by again depressing the start push button switch 90. For safety, a normally closed travel limit switch 97 is provided, see wiring diagram. The limit switch 97 is located on the

right-hand side of the column B and does not show on Figs. 1 and 2 of the drawings, but is so mounted and adapted to be opened by a fixed stop carried by the work head C that the work head C cannot be raised high enough to damage the machine even though the other switches fail.

The control system for the machine is so arranged that the cycle of operations of the machine can be started with the work head C in either of its normally extreme positions. In the embodiment shown the direction in which the cycle of operations is effected is controlled by drum controllers J and K mounted on the switch panel 91. The drum controller J has two positions, designated "up" and "down" respectively. When the drum controller J is set in the "up" position, the circuits to the switches 92 and 94, etc., are set up to execute the cycle of operations wherein the work head C moves in an upward direction to effect the feed, and vice versa. The drum controller K has two positions, designated "forward" and "reverse" respectively. When the controller is set in the "forward" position, the direction of rotation of the hob spindle is such that the hob moves up in front, that is in a clockwise direction as viewed in Fig. 1, and vice versa. Since the feed can be effected in either direction of movement of the work head C and since the cut motor which drives the hob can be reversed, it will be apparent that either "climb" hobbing or "conventional" hobbing can be effected in either direction merely by setting the drum controllers J and K in the selected positions and by so selecting the change gears that the feed is in the proper direction.

The motors 21 and 23 as shown are of the reversible three-phase alternating current type and are adapted to be connected and disconnected from power lines 98, 99 and 100 which in the present instance constitutes a power source for the machine, by solenoid actuated motor controls 101 and 102 of commercial design mounted within the column B. The controls for the motors 21 and 23 and a solenoid operated brake G, etc., can best be described with reference to the operation of the machine. For the present purposes it is considered sufficient to describe but one of the various cycles of operation which the machine shown is capable of performing and the cycle selected is the one wherein "conventional" hobbing is effected and the work head moved in a vertical upwardly direction to produce the relative feed movement between the tool and work.

With the drum controller J set in its "normal" position, the drum controller K set in its "forward" position, and the change gears as shown in the drawings, the hob will rotate in a clockwise direction as viewed in Fig. 1, when the machine is started and the work head C will move in an upwardly direction to effect the relative feed movement between the tool and work. At the beginning of the cycle of operations the work head C is in its "down" position. After the work blank, in the present instance a shaft W to be splined at one end, has been positioned in the work head C, the machine is started by depressing the start push button switch 90, opening the normally closed contacts 103, 104 and closing the normally open contacts 105, 106, 107 and 108. The closing of the contacts 105 and 106 establishes a circuit from the line 99 through the overtravel limit switch 97, wire 110, normally closed stop push button switch 111, wire 112, contacts 105, 106, wire 113, operating solenoid 114 of relay 115, wire 116, contacts 117, 118 of drum controller J, wire

120, contacts 121, 122 of switch 94, wire 123, overload contacts 124, 125 for rapid traverse motor 23, wire 126, overload contacts 127, 128 for cut motor 21 to line 100, energizing the solenoid 114 of relay

115. Energization of the operating solenoid 114 of relay 115 closes the normally open contacts 130, 131 thereof, establishing a circuit from the line 99 through the limit switch 97, wire 110, stop push button switch 111, wire 112, contacts 130, 131, wire 132, operating solenoid 133 of controller panel 101, wire 134, contacts 135, 136 of drum controller J, wire 137, contacts 138, 140 of switch 92, wire 116, contacts 117, 118 of drum controller J, wire 120, contacts 121, 122 of switch 94, wire 123, overload contacts 124, 125, wire 126 and overload contacts 127, 128 to line 100. Energization of the solenoid 133 closes the main contacts 141, 142, 143, 144, 145, 146 for the travel motor 23 connecting the latter to the power lines in such a manner that the motor rotates in a direction to raise the work head C.

When the start push button switch 90 is released, the operating solenoid 114 for the relay 115 will be momentarily deenergized due to the

opening of contacts 105, 106 of start push button switch 90, however, operating solenoid 133 of controller panel 101 will be maintained energized by contacts 147, 148 thereof of which closed simultaneously with the contacts 141 to 146, inclusive.

30 This holding or maintaining circuit is from the line 99 through the overtravel limit switch 97, wire 110, stop push button switch 111, wire 112, contacts 147, 148, wire 132, solenoid 133, wire 134, contacts 135, 136 of drum controller J, wire 137, contacts 138, 140 of switch 92, wire 116, contacts

117, 118 of drum controller J, wire 120, contacts 121, 122 of switch 94, wire 123, overload contacts 124, 125, wire 126, and overload contacts 127, 128 to line 100. When the start push button

40 switch 90 is released completely, the solenoid 114 of relay 115 is again energized by the closing of normally closed contacts 103, 104 of start switch 90. This circuit is from the line 99 through limit switch 97, wire 110, stop push button switch 111,

45 wire 112, contacts 147, 148, controller panel 101, wire 132, contacts 103, 104 of start push button switch 90, wire 113, operating solenoid 114 of relay 115, wire 116, contacts 117, 118 of drum controller J, wire 120, contacts 121, 122 of switch 94, wire 123, overload contacts 124, 125, wire 126, overload contacts 127, 128, to line 100.

50 The traverse or travel motor 23 continues to operate, raising the work head C until just prior to the engagement of the work W with the hob H at which point the stop 93 on the work head C trips the switch 92, opening the previously closed contacts 138, 140 and closing the open contacts 150, 151. The opening of contacts 138, 140 of switch 92 breaks the holding circuit for the solenoid 133, stopping the rapid traverse or travel motor 23, and closing of the contacts 150, 151 of this switch energizes the operating solenoid 152 of the motor controller panel 102 closing the normally open main contacts 153, 154, 155, 156;

55 157, 158 and connecting the cut motor 21 to the power lines 98, 99 and 100 in such a manner that the motor operates in a direction to rotate the hob in a clockwise direction as viewed in Fig. 1, and to continue the elevation of the work head C but at a feed rate. The circuit through the operating solenoid 152 is from the line 99, through the limit switch 97, wire 110, stop push button switch 111, wire 112, contacts 130, 131 of relay 115, wire 132, normally closed contacts 103, 104

70 75 of start push button switch 90, wire 113, solenoid

152, wire 160, contacts 161, 162 of drum controller J, wire 163, contacts 150, 151 of switch 92, wire 116, contacts 117, 118 of drum controller J, wire 120, contacts 121, 122 of switch 94, wire 123, overload contacts 124, 125, wire 126 and overload contacts 127, 128, to line 100.

Upon the energization of the operating solenoid 152 of the controller panel and the closing of the main contacts 153, 154; 155, 156; 157, 158 associated therewith, auxiliary contacts 164, 165 are also closed. The closing of these latter contacts establishes a holding circuit for the operating solenoid 152, control panel 102. This circuit is from the line 99, through the limit switch 97, wire 110, stop push button switch 111, contacts 164, 165, wire 113, solenoid 152, wire 160, contacts 161, 162 of drum controller J, wire 163, contacts 150, 151 of switch 92, wire 116, contacts 117, 118 of drum controller J, wire 120, contacts 121, 122 of switch 94, wire 123, overload contacts 124, 125, wire 126 and overload contacts 127, 128 to line 100. The closing of contacts 150, 151 of switch 94 also closes a circuit to solenoid 166 of relay 167 closing the normally open contacts 170 and 171 thereof establishing an auxiliary maintaining circuit from contact 151 of switch 92 to line 100. The circuit for the solenoid 166 of relay 167 is from line 99 through normally closed overtravel limit switch 97, wire 110, stop push button switch 111, wire 112, contacts 130, 131 of relay 115, wire 132, operating solenoid 166 of relay 167, wire 160, contacts 161, 162 of drum controller J, wire 163, contacts 150, 151 of switch 92, wire 116, contacts 117, 118 of drum controller J, wire 120, contacts 121, 122 of switch 94, wire 123, overload contacts 124, 125, wire 126, and overload contacts 127, 128 to line 100. The auxiliary maintaining circuit mentioned is from wire 116, through contacts 170, 171 of relay 167, wire 172, normally closed contacts 173, 174 of timing relay 175, wire 176, closed contacts 177, 178 of selector switch 180 mounted on the control panel 91, wire 123, overload contacts 124, 125, wire 126, and overload contacts 127, 128 to line 100.

Operation of the cut motor 21 continues until the work blank W is carried to the desired height, whereupon the stop 96 on the work head C actuates the switch 94 to open the closed contacts 121, 122 thereof and close the contacts 181, 182. The closing of contacts 181, 182 of travel limit switch 94 energizes the operating solenoid 183 of timing relay 175 and the operating solenoid 184 of relay 185. The circuit through the operating solenoid 183 is from the line 99 through the overtravel limit switch 97, wire 110, stop push button switch 111, wire 112, contacts 186, 187 of relay 115, wire 188, operating solenoid 183 of relay 175, wire 190, contacts 191, 192 of selector switch 180, wire 193, contacts 194, 195 of drum controller J, wire 196, contacts 181, 182 of travel limit switch 94, wire 123, overload contacts 124, 125, wire 126, and overload contacts 127, 128 to line 100. The circuit through operating solenoid 184 of relay 185 is from the line 99 through the overtravel limit switch 97, wire 110, stop push button switch 111, wire 112, contacts 186, 187 of relay 115, wire 188, solenoid 184 of relay 185, wire 197, contacts 200, 201 of selector switch 180, wire 190, contacts 191, 192 of selector switch 180, wire 193, contacts 194, 195 of drum controller J, wire 196, contacts 181, 182 of travel limit switch 94, wire 123, overload contacts 124, 125, wire 126 and overload contacts 127, 128 to line 100. When the solenoid 184 of relay 185 is energized, it closes a holding or maintaining circuit through

normally open contacts 202 and 203 thereof, which circuit maintains the relay energized. When the contacts 186 and 187 of relay 115 are opened through operation of the timing relay 175, the circuit for the maintaining circuit is from line 99, through overtravel limit switch 97, wire 110, stop push button switch 111, wire 112, contacts 202, 203 of relay 185, wire 204, contacts 205, 206 of timing relay 207, wire 188, operating solenoid 184, relay 185, wire 197, contacts 200, 201 of selector switch 80, wire 190, contacts 191, 192 of selector switch 180, wire 193, contacts 194, 195 of drum controller J, wire 196, contacts 181, 182 of travel limit switch 94, wire 123, overload contacts 124, 125, wire 126, and overload contacts 127, 128 to line 100. Energization of solenoid 184 of relay 185 closes the normally open contacts 208, 210, 211, 212 energizing the operating solenoid 84 for the solenoid brake G, thus allowing the motor shaft of the rapid traverse motor 23 to turn freely, being driven from the feed screw 22, etc., thus stopping the feed movement of the work head C. The circuit for the operating solenoid 84 of the brake G is from the line 99, through the contacts 211, 212 of relay 185, wire 213, solenoid 84, wire 214, and contacts 208, 210 of relay 185 to line 100.

After the opening of the closed contacts 121, 122 of travel limit switch 94 and the closing of the normally open contacts 181 and 182 thereof, the timing relay 175 maintains the operating solenoid 152 of the control panel 102 energized, thus maintaining the cut motor in operation for a predetermined period of time, which period is at least sufficient to allow the work spindle to make one complete revolution, with the result that all of the splines are ended at the same longitudinal point along the work blank. At the end of the aforesaid predetermined period of time, the normally closed contacts 173, 174 of the timing relay 175 open, thus breaking the circuit to the operating solenoid 114 of relay 115, thereby opening the circuit to the operating solenoid 152 of controller panel 102, thus stopping the motor 21 and the circuit to the operating solenoid 166 of relay 167. Upon the closing of the normally closed contacts 215, 216 of relay 115, a circuit is closed for the operating solenoid 217 of timing relay 207. This circuit is from the line 99 through the overtravel limit switch 97, wire 110, stop push button switch 111, wire 112, contacts 202, 203 of relay 185, wire 204, contacts 215, 216, wire 218, operating solenoid 217 of relay 207, wire 190, contacts 191, 192 of selector switch 180, wire 193, contacts 194, 195 of drum controller J, wire 196, contacts 181, 182 of travel limit switch 94, wire 123, overload contacts 124, 125, wire 126, and overload contacts 127, 128 to line 100.

After a predetermined period of time, the timing relay 207 will operate to open its normally closed contacts 205, 206, thereby opening the circuit to operating solenoid 184 of relay 185. The opening of contacts 208, 210, 211, 212 of relay 185 will open the circuit to the operating solenoid 84 of the solenoid brake G. The opening of contacts 202, 203 of relay 185 opens the circuit to the operating solenoid 217 of timing relay 207. The machine is now ready for the return cycle.

After the work blank is removed, the start push button 90 is again depressed whereupon the rapid traverse motor 23 is again actuated but in a reverse direction to lower the work head C to its starting position. When the start push button switch 90 is depressed for the second time, a cir-

cuit is established from the line 99 through the limit switch 97, wire 110, stop push button switch 111, wire 112, contacts 107, 108 of start push button switch 90, wire 220, contacts 221, 222 of relay 115, wire 223, operating solenoid 224 of controller panel 101, wire 193, contacts 194, 195 of drum controller J, wire 196, contacts 181, 182 of switch 94, wire 123, overload contacts 124, 125, wire 126 and overload contacts 127, 128 to line 100.

Energization of the solenoid 224 closes the main contacts 225, 226, 227, 228, 229, 230 associated therewith, connecting the rapid traverse or travel motor 23 to the power lines in such a manner that it operates in the reverse direction, that is, in a direction to lower the work head C. Simultaneously with the closing of the contacts which connect the motor 23 with the power lines, auxiliary contacts 231, 232 are closed establishing a holding circuit for the solenoid 224 after the start push button switch 90 is released. This holding circuit is from the line 99 through the limit switch 97, wire 110, stop push button switch 111, wire 112, contacts 231, 232, wire 233, contacts 221, 222, wire 223, solenoid 224, wire 193, contacts 194, 195 of drum controller J, wire 196, contacts 181, 182, of switch 94, wire 123, overload contacts 124, 125, wire 126, and overload contacts 127, 128 to line 100.

As the work head C drops, the adjustable stop 93, thereon returns the switch 92 to its original position as the stop passes the switch. This re-opens the contacts 150, 151 and closes the contacts 138, 140, thus again setting up the circuit with respect to the cut motor 21 which existed at the beginning of the cycle of operations. The work head C continues to move down until the switch 94 is tripped by the adjustable stop 95 carried by the work head C. This re-opens the contacts 181, 182, stopping the rapid traverse or travel motor 23 and recloses the contacts 121, 122, returning the circuit to the rapid traverse or travel motor 23 to its original condition. After a new work blank is inserted in the work head C, the cycle of operations of the machine can be repeated by again pressing the start push button switch 90.

If it is desired to stop the feed or vertical movement of the work head C at any position in the cycle of operations prior to the completion of the cut in progress, the selector switch 180 can be manually changed to open its closed contacts 177, 178; 191, 192; and 201, 200 and close contacts 261, 262. The closing of contacts 261, 262 of selector switch 180 establishes a circuit from the line 99 through overtravel limit switch 97, wire 110, stop push button switch 111, wire 112, contacts 186, 187 of relay 115, wire 188, operating solenoid 184 of relay 185, wire 197, contacts 261, 262 of selector switch 180, wire 160, contacts 161, 162 of drum controller J, wire 163, contacts 150, 151 of switch 92, wire 116, contacts 117, 118 of drum controller J, wire 120, contacts 121, 122 of switch 94, wire 123, overload contacts 124, 125, wire 126, and overload contacts 127, 128 to line 100. Energization of operating solenoid 184 of relay 185 closes the normally open contacts 208, 210 and 211, 212 thereof, energizing the operating solenoid 84 of the brake G, thus releasing the brake on the armature shaft of the rapid traverse motor 23, allowing the motor to be driven freely by the lead screw 22, thereby stopping the feed movement of the work head C.

If the automatic feed cut-out feature of the machine is not desired, the machine can be operated without it by moving the selector switch

180 to its open position. The opening of contacts 177, 178; 191, 192; and 200, 201 of selector switch 180 prevents the circuits to the solenoids 166, 183, 184 and 217 of the relays 167, 175, 185 and 207 from closing, and the machine operates in a manner similar to the machine shown in the aforesaid Patent No. 2,307,428.

When the operating solenoid 184 of relay 185 is deenergized, the solenoid 84 of the solenoid operated brake G is automatically connected to two of the lead wires 234, 235 and 236 which connect the rapid traverse motor 23 to the control panel 101 so that the brake G will be released whenever the rapid traverse motor is operating. As shown, the circuit is from the lead wire 235 through the normally closed contacts 237, 238 or relay 185, wire 214, operating solenoid 84 of brake G, wire 213, and back through normally closed contacts 249, 241 of relay 185, to lead wire 234. The lead wires 234 and 235 are connected to the drum controller J in such a manner that the direction of rotation of the motor is reversed when the drum controller is changed from "conventional" to "climb" position and vice versa. The wires from the drum controller J to the motor 23 are designated by the reference characters 242, 243 and are connected to reversing terminals 244, 245 and 246, 247 of drum controller J. The wires 234 and 235 are connected to contacts 248 and 249 of the drum controller. The cut motor 21 is connected to the main contacts of control panel 102 by wires 250, 251 and 252. The wires 250 and 251 are connected to contacts 253, 254 of reversing drum controller K and the drum controller is connected to the cut motor by the wires 255 and 256 which, in addition to being connected to the motor terminals, are connected to the reversing contacts 257, 258 and 259, 260 of the drum controller.

As previously stated, the machine shown can be operated so that the cutting operation will be performed in either the "conventional" manner or in a manner to effect "climb" hobbing and the cycle of operations can be effected with the feed taking place in either direction and the automatic feed cut-out feature can be had in any of the cycles mentioned, however, it is considered unnecessary to a complete understanding of the present invention to describe all of these cycles of operations. Both the start push button switch 90 and the stop push button switch 111 are of conventional construction and include ferrules whereby the switches may be set with all of the contacts thereof open. When the start push button switch is set in the aforesaid position, the machine stops at the point in the cycle of operations where normally the cut motor 21 automatically starts. This feature is useful in setting up the machine. With the stop push button set with its contacts open, the machine cannot be operated.

From the foregoing description of the preferred embodiment of the invention, it will be apparent that a new and improved machine of the type referred to has been provided wherein electrically controlled means is provided for automatically stopping the feed movement between the tool and work spindles without stopping the rotation of the spindles and wherein the rotation of the spindles is stopped after a predetermined period of time. While the preferred embodiment shown has been described in considerable detail, it is to be understood that the invention is not limited to the particular construction shown and described and it is the intention to cover hereby all adaptations, modifications and uses thereof.

that come within the practice of those skilled in the art to which the invention relates and within the spirit and scope of the appended claims.

We claim:

1. A hobbing machine of the character described comprising: a frame; a work spindle; means for rotatably supporting said work spindle; a hob or tool spindle; means for rotatably supporting said hob or tool spindle; a lead screw member and a cooperating nut member for producing relative movement between said work spindle and said tool spindle; means for rotatably supporting said lead screw member; means for rotatably supporting said nut member; means for holding one of said members against rotation; power actuated means for rotating the other of said members to effect a relative movement between said spindles; means for initiating operation of said power actuated means; and means for automatically rendering said fifth named means inoperative upon said spindles reaching a predetermined relative position.

2. A hobbing machine of the character described comprising: a frame; a work spindle; means for rotatably supporting said work spindle; a hob or tool spindle; means for rotatably supporting said hob or tool spindle; a lead screw member and a cooperating nut member for producing relative movement between said work spindle and said tool spindle; an electric motor for rotating said spindles and one of said members to effect a relative movement between said spindles at a feed rate; means for preventing rotation of the other of said members; a reversible electric motor for rotating one of said members in opposite directions to effect relative movement between said spindles at a traverse rate; means for effecting operation of said reversible electric motor in one direction whereupon relative movement between said spindles is produced at a traverse rate; means for automatically initiating the operation of said first named electric motor and discontinuing the operation of said reversible electric motor upon said spindles reaching a predetermined relative position whereupon the relative movement between said spindles is continued at the feed rate; means for automatically rendering said third named means inoperative upon said spindles reaching a second predetermined relative position; means for rendering said first named electric motor inoperative after a predetermined lapse of time; means for subsequently effecting the operation of said reversible electric motor but in such a manner that it operates in a reverse direction whereupon relative movement between said spindles is produced in the opposite direction at a traverse rate; and means for automatically discontinuing the operation of said reversible electric motor upon said spindles reaching their initial relative position.

3. A hobbing machine of the character described comprising: a frame; a work spindle; means for rotatably supporting said work spindle; a hob or tool spindle; means for rotatably supporting said hob or tool spindle; a lead screw member and a cooperating nut member for producing relative movement between said work spindle and said tool spindle, one of said members being adapted to drive the other; an electric motor for rotating said spindles and both of said members, one of said members being driven through the other; an electric solenoid controlled brake operatively connected to the member of said members being driven by the other member thereof; a reversible electric motor for rotating

one of said members in opposite directions to effect relative movement between said spindles at a traverse rate; means for connecting said reversible electric motor with a power source whereupon relative movement between said spindles is effected at a traverse rate; means for automatically connecting said first named electric motor with a power source, actuating said brake to prevent rotation of said member to which it is operatively connected and disconnecting said reversible electric motor from the power source, upon said spindles reaching a predetermined relative position whereupon the relative movement between said spindles is continued at a feed rate; means for automatically rendering said brake inoperative to prevent rotation of said member with which it is operatively connected upon said spindles reaching a second predetermined relative position; means for automatically disconnecting said first named electric motor from the power source after a predetermined lapse of time; means for subsequently connecting said reversible electric motor with a power source but in such a manner that it operates in a reverse direction whereupon relative movement between said spindles is produced in the opposite direction at a traverse rate; and means for automatically disconnecting said reversible electric motor from said power source upon said spindles reaching their initial relative position.

4. A hobbing machine of the character described comprising: a frame; a work spindle; means for rotatably supporting said work spindle; a hob or tool spindle; means for rotatably supporting said hob or tool spindle; a lead screw member and a cooperating nut member for producing relative movement between said work spindle and said tool spindle, means for supporting one of said members in said frame for free rotation relative thereto whereby it is capable of being driven by the other; an electric motor for rotating said spindles and both of said members; an electric solenoid controlled brake operatively connected to said member adapted to be driven by the other of said members; a reversible electric motor for rotating one of said members in opposite directions to effect relative movement between said spindles at a traverse rate; means for connecting said reversible electric motor with a power source whereupon relative movement between said spindles is effected at a traverse rate; means for automatically connecting said first named electric motor with a power source, actuating said brake to prevent rotation of said member to which it is operatively connected and disconnecting said reversible electric motor from the power source, upon said spindles reaching a predetermined relative position whereupon the relative movement between said spindles is continued at a feed rate; means for automatically rendering said brake inoperative to prevent rotation of said member with which it is operatively connected upon said spindles reaching a second predetermined relative position; means for automatically disconnecting said first named electric motor from the power source after a predetermined lapse of time; means for subsequently connecting said reversible electric motor with a power source but in such a manner that it operates in a reverse direction whereupon relative movement between said spindles is produced in the opposite direction at a traverse rate; and means for automatically disconnecting said reversible electric motor from said power source upon said spindles reaching their initial relative position.

5. A hobbing machine of the character described comprising: a frame; a work spindle; means for rotatably supporting said work spindle, a hob or tool spindle; means for rotatably supporting said hob or tool spindle; a lead screw and a cooperating nut for producing relative movement between said work spindle and said tool spindle; means for rotatably supporting said nut in said frame whereby said nut is capable of being driven by said lead screw; an electric motor for rotating said spindles and said lead screw; an electric solenoid controlled brake operatively connected to said nut; a reversible electric motor for rotating said nut in opposite directions to effect relative movement between said spindles at a traverse rate; means for connecting said reversible electric motor with a power source whereupon relative movement between said spindles is effected at a traverse rate; means for automatically connecting said first named electric motor with a power source, actuating said brake to prevent rotation of said nut and disconnecting said reversible electric motor from the power source, upon said spindles reaching a predetermined relative position whereupon the relative movement between said spindles is continued at a feed rate; means for automatically rendering said brake inoperative to prevent rotation of said nut upon said spindles reaching a second predetermined position; means for automatically disconnecting said first named electric motor from the power source after a predetermined lapse of time; means for subsequently connecting said reversible electric motor with a power source but in such a manner that it operates in a reverse direction whereupon relative movement between said spindles is produced in the opposite direction at a traverse rate; and means for automatically disconnecting said reversible electric motor from said power source upon said spindles reaching their initial relative position.

6. A hobbing machine of the character described comprising: a frame; a hob or tool spindle; means for rotatably supporting said hob or tool spindle in said frame; a work head slidably supported on said frame; a work spindle; means for rotatably supporting said work spindle in said work head; a lead screw member and a cooperating nut member for moving said work head; means for rotatably supporting one of said members in said work head; means for rotatably supporting the other of said members in said frame; means for holding one of said members against rotation; power actuated means for rotating said spindles and the other of said members means for initiating operation of said power actuated means; means for automatically rendering the fifth named means ineffective to prevent rotation of said member associated therewith upon said work head reaching a predetermined position; and means for subsequently rendering said power actuated means ineffective to rotate said spindles.

7. A hobbing machine of the character described comprising: a frame; a hob or tool spindle; means for rotatably supporting said hob or tool spindle in said frame; a work head slidably

supported on said frame; a work spindle; means for rotatably supporting said work spindle in said work head; a lead screw member and a cooperating nut member for moving said work head; means for rotatably supporting one of said members in said work head and the other of said members in said frame; an electric motor for rotating said spindles and said member rotatably supported in said work head; means for selectively preventing rotation of said member rotatably supported in said frame; a second electric motor for rotating one of said members in opposite directions; means for effecting operating of said second electric motor in one direction; means for automatically initiating operation of said first named electric motor and discontinuing the operation of said second electric motor upon said spindles reaching a predetermined relative position; means for automatically rendering the fourth named means inoperative to prevent rotation of said member associated therewith upon said work head reaching a second predetermined position; means for rendering said first means inoperative after a predetermined lapse of time; means for subsequently effecting the operation of said second means but in a reversed direction; and means for automatically discontinuing the operation of said second means upon said work head reaching its starting position.

8. A hobbing machine of the character described comprising: a frame; a hob or tool spindle; means for rotatably supporting said hob or tool spindle in said frame; a work head slidably supported on said frame; a work spindle; means for rotatably supporting said work spindle in said work head; a lead screw member and a cooperating nut member for moving said work head; means for rotatably supporting one of said members in said work head and the other of said members in said frame; an electric motor for rotating said spindles and said member rotatably supported in said work head; means for preventing rotation of said member supported in said frame; a second electric motor for rotating one of said members in opposite directions; means for effecting operating of said second electric motor; means for automatically initiating operation of said first electric motor and discontinuing the operation of said electric motor upon said spindles reaching a predetermined relative position; electric means actuated by the movement of said work head for automatically rendering said fourth named means inoperative to prevent rotation of said member rotatably supported in said frame upon said work head reaching a second predetermined position; means for rendering said first means inoperative after a predetermined lapse of time; means for subsequently effecting the operation of said second means but in a reversed direction; and means for automatically discontinuing the operation of said second means upon said work head reaching its starting position.
